UNITED STATES PATENT OFFICE.

ALBERT D. LEGG, OF BALTIMORE, MARYLAND.

ELAPSED-TIME INDICATOR.

1,201,205.

Specification of Letters Patent. Patented Oct. 10, 1916.

Application filed January 3, 1916. Serial No. 69,882.

To all whom it may concern:

Be it known that I, ALBERT D. LEGG, a citizen of the United States, and a resident of the city of Baltimore, in the State of Maryland, have invented a certain new and useful Improvement in Elapsed-Time Indicators, of which the following is a specification.

My present invention relates particularly to improvements in charts or computing devices for indicating the elapsed time for "return premiums" on fire insurance policies, whereby to do away with certain disadvantages present in these devices as now used.

The main objections to the devices now in use are the extreme length of the charts necessary to permit the indication of elapsed time up to one year and the unnecessary length of the indicating member itself which, as a slide, must in most instances be extended some distance beyond the chart itself.

The primary object of my invention is, therefore, to provide a double chart together with an endless flexible indicating member which need not at any time extend beyond the edges of the chart and which has its indicating month data arranged in a novel and convenient form to coöperate with the chart itself, thus obviating the above disadvantages and promoting other advantages to be hereinafter mentioned.

In the accompanying drawings illustrating my invention, and forming a part of this specification Figure 1 is a plan view of a part of my improved chart including the indicating member. Fig. 2 is an enlarged section taken through the device longitudinally of one end of the indicating member and substantially on line 2—2 of Fig. 1. Fig. 3 is a sectional view taken through the entire device, longitudinally of the indicating member. Fig. 4 is a detail section taken through the device transversely of the indicating member and substantially on line 3—3 of Fig. 1, and Fig. 5 is a partial section taken as in Fig. 4, and illustrating a slightly modified form of construction.

Referring now to these figures, A indicates the main body of the chart itself which may be formed of any material suitable for the purpose and which is preferably provided upon at least one face, with a figure sheet A' and which, as seen in Fig. 1, is divided into one hundred and eighty-two

transverse columns and into longitudinal columns of numeral values, the latter being arranged in series of which one series is headed as best seen in the figure last mentioned, in tens of dollars, another series in dollar units, and still another series into cents in multiples of five. It will also be noted by reference to Fig. 1, that the sheet A' is provided with spaced longitudinal number columns A² and A³, the numbers therein increasing from 1 to 182 in the column A² and from 183 to 364 in the column A³, the numbers being within the transverse columns above mentioned.

In the space between the number columns A² and A³, is arranged the upper run of an endless flexible indicating member B, the lower run of which travels across the lower surface of the chart A and the ends of which travel around rollers C, mounted in conformable recesses in the relatively opposite edges of the chart A between the number columns A² and A³ of its sheet A', it being noted that this indicating member or belt B is provided along its opposite edges at points immediately adjacent the number columns A² and A³, with spaced columns in which are arranged in successive order the numbered days of succeeding months during a year, each column being preferably composed of eighteen successive months in order that with the months of the two columns opposite to one another preceding each other by six months, any given number of days between any two periods of a complete year may be indicated upon the face of the chart.

The indicating belt B may be provided with buttons or handles B' at spaced points as shown in Figs. 1 and 2, or, as also shown in Fig. 1, the shaft C' of the roller C may be extended laterally beyond one edge of the chart A and provided with knobs C² by which the belt may be turned as desired. Furthermore, as seen by reference to Figs. 4 and 5, the belt B may either travel upon the surface of the sheet A' as in the former figure, or may travel upon the face of the chart body A as seen in Fig. 5, between spaced portions of the sheet A'. As before stated the belt B preferably contains in each of its side columns eighteen successive months for the reasons noted, and with the rollers C placed as shown so that no portion of the belt extends beyond the minimum sized chart, it is necessary to take up certain

slack in the length of the belt and this may be done by means of rollers D at the rear of the chart as shown in Fig. 3. However, the chart itself may be lengthened so as to obviate the necessity of take up rollers of this nature. In any event it will be seen that the arrangement I propose enables another chart sheet A² as shown in Fig. 2 to be placed upon the rear face of the chart body A, this latter chart sheet being where employed, designed for use with a different set of numeral values or in computing short rate return premiums in the same way that *pro rata* return premiums are computed upon the obverse side of the chart, as will now be described. With the device as thus described, *pro rata* return premiums may be readily indicated by moving the belt B so that the particular day of the particular month upon which the insurance is canceled is immediately above the numeral 1 in the number column A² of the chart sheet A'. Thus, supposing the day of cancellation to be December 15 upon a policy running to February 25 of the succeeding year, the 15th day of December in the right hand column of the belt B is placed immediately above the numeral 1 in the number column A², and it will then be found that the 25th day of February in the right hand column of the belt is opposite numeral 72 of the number column A² indicating the correct number of days, so that by following out the transverse column in which the numeral 72 is arranged at the right hand side of the chart, the amount to be returned will appear in the value columns arranged in the series as above described. Thus also, referring to Fig. 1, if the date of cancellation is November 30, with the policy to run until May 10 of the succeeding year, the belt is placed as shown and it will be seen that the 10th of May in the right hand column of the belt is opposite the numeral 161 in the number column A² of the chart and opposite the amount \$4.41 which would be the return value if the premium of the policy is \$10.00. Likewise, should the day of cancellation be the same and the policy to run until November 28 of the succeeding year, it will be seen from Fig. 1 that the parts properly placed bring the 28th of November in the left hand column of the belt B opposite the numeral

363 in the number column A³ of the chart sheet A' and opposite the amount \$9.94 55 which would be the return value upon a policy, the premium of which is \$10.00.

It will thus be seen that I provide a computing chart of this nature which, though of minimum size and much smaller and more 60 readily utilized than those now in use, may indicate with but a single movement of the indicating web, elapsed time within an entire year, and which is capable of convenient use without the extension of any portion of 65 the indicating member beyond the limits of the chart sheet itself, or stand in the way of either the user or passers-by.

I claim:—

1. A double chart of the character described having spaced number columns, in one of which the numerals progress from one to one-hundred and eighty-two and in the other of which the numerals progress from one hundred and eighty-three to three 75 hundred and sixty-four, and an endless shiftable indicating member movable in the space between said number columns and having spaced longitudinal columns for successive months and days thereof, of which any particular day may be registered with any of the numerals of the said number columns, and the opposing months of the two days columns of the said indicating member being six months in advance of one another, 80 85 for the purpose described.

2. A chart of the character described having spaced number columns, in one of which the numerals progress from one to one-hundred and eighty-two and in the other of 90 which the numerals progress from one hundred and eighty-three to three-hundred and sixty-four, and an endless shiftable indicating belt mounted around the chart to travel longitudinally in the space between said 95 number columns and having along its opposite edges day columns for successive months, the belt being shiftable within the limits of the chart to register any desired day with any of the numerals of the said number columns, and the opposing months of the two 100 columns of said indicating belt being six months in advance of one another, all for the purpose described.

ALBERT D. LEGG.
